UNITED STATES PATENT OFFICE.

CLIFTON D. PETTIS AND PERCY H. BATTEN, OF CHICAGO, ILLINOIS, ASSIGNEES, BY
MESNE ASSIGNMENTS, TO AMERICAN BRAKE SHOE & FOUNDRY COMPANY, A COR-
PORATION OF NEW JERSEY.

BRAKE-SHOE.

1,104,924.

Specification of Letters Patent. Patented July 28, 1914.

Application filed December 10, 1909. Serial No. 532,317.

To all whom it may concern:

Be it known that we, CLIFTON D. PETTIS and PERCY H. BATTEN, citizens of the United States, and residents of Chicago, in the county of Cook and State of Illinois, have invented certain new and useful Improvements in Brake-Shoes, of which we do declare the following to be a full, clear, and exact description, reference being had to the accompanying drawing, forming part of this specification.

This invention relates more particularly to that class of brake shoes in which the cast metal body of the shoe is reinforced by a back of soft steel or like ductile metal, and the objects of the invention are, first, to provide a more effective and stronger back for the shoe.

An example of the type of brake shoe to which our invention relates is shown in Letters Patent No. 924,930, granted to the National Brake Shoe Company, as assignee of Clifton D. Pettis, June 15, 1909.

The invention consists in the features of improvement hereinafter described, illustrated in the accompanying drawings and particularly pointed out in the claims at the end of this specification.

Figure 1 is a plan view showing how the sheet metal backs are formed from a continuous strip. Fig. 2 is a plan view upon a larger scale than Fig. 1, showing how the initial bending of the back plate is effected. Fig. 3 is a view in side elevation of the partially formed back plate illustrated in Fig. 2. Fig. 4 is a plan view showing the completed back plate embodying our invention. Fig. 5 is a view in side elevation of the back plate. Fig. 6 is a view in vertical transverse section on line 6—6 of Fig. 8, and Fig. 7 is a view in cross section on line 7—7 of Fig. 9, these sections showing also the cast metal body of the shoe united to the ductile metal back. Fig. 8 is a plan view of the shoe complete. Fig. 9 is a view in longitudinal section on line 9—9 of Fig. 8. Fig. 10 is a view in transverse section on line 10—10 of Fig. 8.

The body 12 of the shoe may be formed of cast iron of suitable quality and shape, and the reinforcing back may be of soft steel or other ductile metal. The invention is shown as applied to a brake shoe more especially designed for the driving wheels of

locomotives; that is to say, the shoe has a braking-face 14 adapted to bear upon the tread of the wheel, and a groove 15 adapted to receive the flange of the wheel. The reinforcing back 16 extends nearly from side to side and approximately from end to end of the body of the shoe at its back. Preferably, the curved portion of the back 16, which extends over the flange engaging portion of the shoe body, is provided with a series of openings 17 to permit the cast metal shoe body to more effectively engage and interlock with the reinforcing back. In the back 16 of the shoe there is formed a longitudinal opening 18, opposite one end of which a hole will be formed in the body of the shoe to receive the usual retaining bolt that co-operates in connecting the brake shoe to the brake head. At one end of the shoe there is formed an attaching lug 22 that is integral with the back 16, this lug being bent upwardly and backwardly, as shown in the drawings, and being formed with a central arch or corrugation 23, in order to give increased strength thereto.

The end portion of the back 16 of the shoe is formed with a longitudinal depression or corrugation 24 that corresponds and unites with the corrugation 23 of the lug 22. Preferably, this depression or corrugation 24 at the end of the back 16 has its forward end tapering and terminates at a point at or near one end of the slot 18. The purpose of the depression or corrugation 24 is two-fold, viz: to give increased strength to the end portion of the shoe, and to avoid any sharp cutting edge that might tend to cut away the tread surface of the wheel, as the body of the shoe is worn down.

It will be understood that the back 16 of the shoe will be set in the mold and the metal body of the shoe will be cast thereon in manner well understood by those familiar with the manufacture of this type of brake shoe. The cast metal will flow into the openings 17 and 18 of the back 16 and around the base of the lug 22. In practice it will be found that, as the cast metal body of the shoe reaches the extreme of its wear, the longitudinal corrugation 24, tapering inwardly, as it does, will afford no sharp cutting edge that might tend to groove or mar the tread surface of the wheel. The corrugation 23 formed centrally of the lug 22 will

give great rigidity to this lug and, being located in line with the corrugation 24 in the back 16 of the shoe, the two corrugations can be formed at one and the same operation.

The feature of forming an attaching lug with a corrugation that extends beyond the base of the lug and for a distance into the body of the back plate is an important one, since it strengthens the lug—particularly at its base, where it is subject to excessive strain and where there would be danger of breakage, if the corrugation terminated at such point.

15 By reference more particularly to Fig. 10 of the drawings, it will be seen that the hole 19 in the back plate, at the end of the slot 18, is larger than the hole 13 formed in the cast metal body 12 of the shoe to admit the

20 usual attaching bolt whereby the shoe is connected to the brake head, and it will be noticed that a shoulder or liner of cast metal is thus interposed between the attaching bolt and the edge of the hole 19. One advantage 25 in thus forming the hole 19 materially larger than the hole 13 is that the contact of the attaching bolt with the edge of the back 16 is avoided and the danger of cutting the bolt is correspondingly lessened.

30 By reference more particularly to Figs. 4, 5 and 6 of the drawings, it will be seen that the back plate 16 has one of its ends formed with a broad notch 25 and a narrow notch 26, and at its opposite end, adjacent the hook 23, the back plate is formed with a notch 27. The notch 25 corresponds in width and shape with the end portion of the lug 22. By forming the broad notch 25, and, preferably also, the narrow notch 26, in one end of the 40 shoe, the cast metal end lug 28 may be formed of greater strength than would be possible if the end of the back plate 16 were not notched, but extended unnotched beneath the end lug 28.

45 In forming the back of the shoe (see Figs. 1, 2 and 3) a strip of metal of suitable width and thickness is first placed beneath a set of dies comprising dies 30 adapted to form the several holes 17, a die 31 adapted to form 50 the long slot 18 and its end hole 19, a die 32 adapted to form the notch 26 at one end of the plate, and dies 33 and 34 adapted to cut away the metal between the adjacent back plates and at the sides of the attaching lug

22. At the same time that these several dies 55 perform their operation, a knife simultaneously operates to sever the tongue or lug 22 from that part of the metal strip that is to form the adjacent back, thereby forming the notch 25 at the adjacent end of the next 60 succeeding back plate. Each back plate having thus been made in flat shape is next placed within a suitable die that gives to the plate the corrugation that comes opposite the flanged portion of the finished shoe and 65 gives to the plate and its lug 22 the corrugations 24 and 23, respectively. By the operation of these dies the lug 22 is left at an angle of about 45° to the back plate, so that it may be readily operated on by the next 70 succeeding set of dies, which completes the bending of the lug 22 to the shape shown in Figs. 4 and 5 of the drawings.

Having thus described our invention, what we claim as new, and desire to secure 75 by Letters Patent, is:—

1. A reinforcing back for brake shoes, comprising a plate of tough metal having at one end a corrugation extending inwardly toward the face of the shoe and tapering 80 toward the center of the shoe.

2. A reinforcing back for brake shoes, having at one end an attaching lug provided with a corrugation and having the end portion of the back provided with a corrugation 85 corresponding to that of the lug and joining therewith.

3. A reinforcing back for brake shoes, comprising a plate of tough metal having at one end an attaching lug formed integral 90 therewith, said lug and the end portion of said back being provided with joined corrugations, the inner end of the corrugation in the back being tapered.

4. A brake shoe comprising a cast metal 95 body and a reinforcing back plate of ductile metal, both of said parts having holes formed therethrough to receive an attaching bolt, the hole of the back plate being larger than the hole of the cast metal body, whereby a liner of cast metal is formed within the 100 hole of the back plate.
